AIR CONDITIONING

Hugo M. Ullstrand, Evansville, Ind., assignor to
Servel, Inc., New York, N. Y., a corporation of
Delaware

Application April 13, 1938, Serial No. 201,655

6 Claims. (Cl. 62—119.5)

My invention relates to air conditioning, and more particularly to conditioning of air with a refrigeration system of the kind employing evaporation of refrigerant fluid in the presence of an inert gas or auxiliary agent.

In air conditioning the treated air may be cooled below its dew-point to effect condensation of water vapor, so that the absolute humidity of the air will be reduced. To effect such dehumidification, the treated air may be conducted in thermal transfer relation with a cooling element of a refrigeration system. After dehumidification, the resulting cold air is at a temperature which is too low for comfort. In order that cold dehumidified air may be employed for comfort cooling, it is necessary to increase the dry bulb temperature of treated air before introduction to the enclosure to be conditioned.

It is an object of the invention to accomplish cooling of air for dehumidification and reheating with a refrigeration system of the kind employing an inert gas or auxiliary agent, particularly to effect such cooling and reheating by fluids circulating in the refrigeration system.

Another object of the invention is to condition air in an enclosure by flowing the air past a cooling element having a gradient temperature in such a manner that air passes in heat exchange relation with successive portions of the cooling element having increasingly lower temperatures.

The above and other objects and advantages of the invention will be more fully understood upon reference to the following description and accompanying drawings forming a part of this specification, and of which:

Fig. 1 illustrates more or less diagrammatically air conditioning apparatus embodying the invention;

Fig. 2 more or less diagrammatically illustrates a refrigeration system and an enlarged fragmentary view of an air duct in Fig. 1 within which are disposed parts of the refrigeration system; and

Fig. 3 is a sectional view taken on line 3—3 of Fig. 2 to illustrate more clearly the arrangement of the parts within the air duct.

In Fig. 1 a duct 10 through which air is circulated is connected to an enclosure 11. The duct 10 is provided with a fan 12 which may be driven by a motor 13. The fan 12 draws air to be conditioned through inlet 14, past cooling and reheating unit 15 located in duct 10, and discharges the conditioned air into enclosure 11. The path of flow of air is indicated by the arrows in Fig. 1. A duct 16 is provided for exhausting or discharging air from enclosure 11.

The air to be conditioned may comprise fresh air or a mixture of fresh air and air discharged from enclosure 11. When the air to be conditioned is a mixture of fresh air and withdrawn air, duct connections may be provided to vent part of the air withdrawn in duct 16 to the atmosphere and the remainder thereof may be mixed with fresh air and introduced at inlet 14. Other arrangements may also be provided for recirculating air withdrawn from enclosure 11. Systems of this character for recirculating part of the withdrawn air form no part of the present invention, however, since the principles of the invention may be utilized in any air conditioning system in which air to be conditioned is dehumidified and then reheated for comfort cooling.

The cooling and reheating unit 15 forms part of an absorption refrigeration system of the kind containing an inert gas or auxiliary agent. As shown in Fig. 2, such a system includes a generator 17, condenser 18, evaporator 19 and absorber 20. The system contains a solution of refrigerant in absorption liquid, such as ammonia in water, for example, and also an auxiliary agent or inert gas, such as hydrogen.

The generator 17 is heated in any suitable manner, as by a gas burner 21, for example, whereby refrigerant vapor is expelled from solution in generator 17. The refrigerant vapor flows upwardly through a stand-pipe 22 and a conduit 23 into an air-cooled condenser 18 where the vapor is condensed into liquid.

The condenser 18 includes an upper section 18a, an intermediate section 18b, and a lower section 18c, and the evaporator or cooling element 19 includes a plurality of sections 19a, 19b and 19c arranged alongside each other within duct 10. Refrigerant liquefied in upper condenser section 18a flows through a conduit 24 into cooling section 19a. Refrigerant not liquefied in condenser section 18a flows through an upper looped portion of conduit 24 into intermediate condenser section 18b in which it is liquefied. Liquid refrigerant flows from intermediate condenser section 18b through conduit 25 into cooling section 19b. Refrigerant not liquefied in intermediate section 18b flows through an upper looped portion of conduit 25 into lower condenser section 18c in which it is liquefied. Liquid refrigerant flows from lower condenser section 18c into gas separating chamber 26 and thence through conduit 27 into cooling section 19c.

The cooling sections 19a, 19b and 19c forming cooling element or evaporator 19 are disposed in the path of flow of air in duct 10. These cooling sections may be provided with fins to present a relatively large heat transfer surface over which the air to be conditioned passes. Refrigerant fluid in the cooling sections evaporates and diffuses into inert gas which enters through an upper manifold 28, thereby producing a refrigerating or cooling effect. The rich gas mixture of refrigerant vapor and inert gas formed in the cooling sections flows from the lower parts thereof into a lower manifold 29 and thence through conduit 30 to absorber 20.

In absorber 20 the rich gas mixture flows counter-current to downwardly flowing weak absorption liquid which enters through a conduit 31. The absorption liquid absorbs refrigerant vapor from the inert gas, and inert gas weak in refrigerant vapor flows from absorber 20 through a conduit 32 and upper manifold 28 into the upper parts of cooling sections 19a, 19b and 19c.

Absorption liquid enriched in refrigerant flows from the lower part of absorber 20 through a conduit 33, outer passage of a liquid heat exchanger 34, and conduit 35 into generator 10. Liquid is raised in the generator by a thermosiphon tube 36 and flows back to the generator through stand-pipe 22. Refrigerant vapor expelled out of solution in generator 17, together with refrigerant vapor entering through thermosiphon tube 36, flows upwardly through stand-pipe 22 and conduit 23 to condenser 18, as explained above.

The weakened absorption liquid from which refrigerant has been expelled flows from generator 17 through conduit 37, inner passage of liquid heat exchanger 34, and conduit 31 to the upper part of absorber 20. This circulation of absorption liquid is effected by raising liquid by means of thermosiphon tube 36.

A coil 38 arranged in thermal exchange relation with absorber 20 is connected by conduits 39 and 40 to a looped coil 41 provided with cooling fins 42. The coils 38 and 41 and connecting conduits form a secondary heat transfer system which may be partly filled with a suitable volatile liquid. Evaporation of liquid in coil 38 takes up heat liberated with absorption of refrigerant vapor in absorber 20, and condensation of vapors in coil 41 gives up heat to air flowing over the surfaces of looped coil 41 and fins 42.

The lower end of condenser 18 is connected by conduit 43, vessel 44 and conduit 45 to the gas circuit, as to the upper end of conduit 30, for example, so that any inert gas which may pass through the condenser can flow into the gas circuit. Refrigerant vapor not condensed in condenser 18 flows through conduit 43 to displace inert gas in vessel 44 and force gas therefrom into the gas circuit through conduit 45. By forcing gas into the gas circuit in this manner, the total pressure in the system is raised whereby an adequate condensing pressure is obtained to insure condensation of refrigerant vapor in condenser 18.

When the refrigeration system is operating, inert gas circulates continuously in the gas circuit including absorber 20 and cooling element or evaporator 19. This circulation of gas in the gas circuit is due to the difference in specific weight of the column of rich gas in cooling element 19, lower manifold 29 and conduit 30; and the column of weak gas in absorber 20, conduit 32 and

upper manifold 28. Since the rich gas is heavier than the weak gas, force is produced within the system for causing flow of rich gas toward absorber 20 and flow of weak gas toward cooling sections 19a, 19b and 19c forming cooling element 19.

As illustrated most clearly in Fig. 3, the cooling sections are shown more or less diagrammatically in the form of looped coils. The lower ends of conduits 24, 25 and 27 are each connected at 46 to the upper parts of cooling sections 19a, 19b and 19c, respectively. The lower ends of conduits 24, 25 and 27 are U-shaped to provide liquid seals to prevent non-condensable gas from entering the cooling sections from condenser 18. Since gas weak in refrigerant enters the upper parts of the cooling sections and enriched gas leaves the lower parts of the cooling sections, the gas in the lower parts of the cooling sections contains a greater amount of refrigerant vapor than the gas in the upper parts thereof. The partial vapor pressure of refrigerant in the gas is a gradient, so that the evaporating temperature of liquid refrigerant is also a gradient, the evaporating temperature of liquid being lower in the upper parts of the cooling sections.

In order to dehumidify air the dry bulb temperature of the air must be reduced below its dew-point. Since sensible heat is removed from air to reduce the temperature thereof from a high 30 to a lower value, a cooling element having a gradient temperature can be effectively utilized to effect cooling of the air.

In accordance with the invention, therefore, air drawn into duct 10 through inlet 14 flows past cooling sections 19a, 19b and 19c from the high temperature parts to the low temperature parts thereof. As air is drawn past the cooling sections it first flows over the surfaces of the lower parts of the looped coils. In the lower 40 parts of the cooling sections 19a, 19b and 19c, rich gas is leaving through lower manifold 29 and flowing toward absorber 20. This rich gas is relatively cold and can be utilized to abstract sensible heat from air and thereby precool the 45 same. For efficient operation, liquid refrigerant preferably is not reaching the extreme lower portions of the cooling sections, whereby heat transfer from air to rich gas will be effected to precool the air.

The air flowing upwardly past the cooling sections contacts increasingly colder surfaces, and sensible heat is removed therefrom to bring the temperature of the air down to the dew-point. In the upper parts of the cooling sections at the 55 regions where liquid refrigerant is first introduced into the presence of weak gas, the lowest temperatures prevail. In the colder upper parts of the cooling sections the air is cooled below its dew-point, and the resulting moisture condensed from the air drips from the cooling sections. The water may be collected in any suitable manner (not shown), and a drain-pipe provided for carrying away the water.

By flowing the air in the direction of increasing 65 coldness of the cooling sections, the entire surface presented to the air by the cooling sections is effectively utilized to cool and dehumidify the air. With the arrangement provided the air is in counter-flow or flows counter-70 current to the gas and liquid refrigerant in the cooling sections 19a, 19b and 19c. The temperature of the air flowing past the cooling sections is also a gradient, the air temperature decreasing as it flows past the cooling sections until it 75

is cooled below its dew-point, whereby moisture is condensed out of the air. The lowest temperature at the upper parts of the cooling sections determines the resulting low temperature of the cold dry air after dehumidification. The temperature of the cold dry air is too low for comfort, and, in order to provide conditioned air for comfort cooling, it is desirable to increase the dry bulb temperature of the air before introduction into enclosure 11.

In accordance with the invention, sensible heat is added to the cold dry air by heat transfer from fluids in the refrigeration system. Liquid refrigerant flowing from condenser 18 and weak gas flowing from absorber 20 are relatively warm. In order that these fluids may be utilized to reheat the dehumidified air, the conduits in which these fluids are conducted to the cooling sections are disposed within duct 10. As shown most clearly in Fig. 3, a portion of conduit 27 in which liquid refrigerant is flowing to cooling section 19c is disposed within duct 10. Above the connection of conduit 27 to cooling section 19c at 46, the looped coil is extended upwardly to provide a portion 9c through which weak gas flows from upper manifold 28.

In conduit 27 and portion 9c of the looped coil, liquid refrigerant and weak gas are flowing out of contact with each other to the upper part of cooling section 19c. A refrigerating effect is produced only when liquid refrigerant flows into the presence of weak gas at 46, whereupon refrigerant evaporates and diffuses into inert gas to abstract heat from air passing over the surfaces of the cooling section.

The conduit 27 and portion 9c of the looped coil provide separate paths of flow for liquid refrigerant and weak gas within duct 10. These fluids are relatively warm and by heat transfer add sensible heat to cold dry air which has been dehumidified. After flowing upward past the cooling section 19c, therefore, the dehumidified air is reheated by passing over the surfaces of conduit 27 and portion 9c of the looped coil forming cooling section 19c.

The looped coils forming cooling sections 19a and 19b are also provided with extreme upper coil portions 9a and 9b similar to the portion 9c. Likewise, the conduits 24 and 25 through which liquid refrigerant flows into cooling sections 19a and 19b are also disposed within duct 10 in a manner similar to conduit 27. To increase the effective heat radiating surface, conduits 24, 25 and 27 and portions 9a, 9b and 9c of the looped coils may be provided with heat transfer fins.

In addition to reheating dehumidified air, the transfer of heat from warm liquid refrigerant and weak gas to the air is advantageous in that these fluids are precooled before flowing into the presence of each other in the cooling sections. Conduits 24, 25 and 27 may be arranged in thermal exchange relation with the upper portions 9a, 9b and 9c of the looped coils, so that precooled liquid refrigerant and precooled weak gas will flow together at substantially the same low temperature. By precooling liquid refrigerant and weak gas entering the upper parts of the cooling sections, evaporation of liquid refrigerant will take place at a lower temperature in the upper parts of the cooling sections.

It will be noted that conduit 30 through which rich gas flows to absorber 20 is out of thermal exchange relation with conduit 20 through which warm weak gas flows to upper manifold 28. The conduits through which warm fluid flows to the

cooling sections may be insulated at the portions outside duct 10 to prevent loss of heat.

Instead of arranging the cooling sections as shown in Fig. 2, these cooling sections may be arranged almost in a horizontal position and one above the other in a horizontally disposed duct. With such arrangement, the overall height of the condenser can be reduced.

While a single embodiment of the invention has been shown and described, such variations and modifications are contemplated which fall within the true spirit and scope of the invention, as pointed out in the following claims.

What is claimed is:

1. A method of conditioning air in an enclosure with the aid of a refrigeration system employing evaporation of liquid refrigerant fluid in the presence of an auxiliary fluid at a place of cooling, which includes flowing air to the enclosure, passing such air in heat exchange relation with the place of cooling to abstract heat from said air to cool and dehumidify the same, flowing liquid refrigerant fluid and auxiliary fluid out of contact with each other to the place of cooling, and reheating said air after dehumidification by transferring sensible heat thereto from liquid refrigerant fluid and auxiliary fluid before these fluids reach the place of cooling.

2. A method of conditioning air in an enclosure with the aid of a refrigeration system employing evaporation of liquid refrigerant fluid in the presence of an inert gas at a place of cooling, which includes flowing air to the enclosure, passing such air in heat exchange relation with the place of cooling to abstract heat from said air to cool and dehumidify the same, circulating the inert gas between said place of cooling and a place of absorption with the gas flowing to the place of absorption being out of thermal exchange relation with the gas flowing to the place of cooling, and reheating the air after dehumidification by transferring heat thereto from gas flowing from the place of absorption to the place of cooling.

3. A method of conditioning air in an enclosure with the aid of a refrigeration system employing evaporation of refrigerant fluid in the presence of an inert gas at a place of cooling, which includes flowing air to the enclosure, passing such air in heat exchange relation with the place of cooling to abstract heat from said air to cool and dehumidify the same, flowing warm refrigerant fluid and auxiliary fluid to said place of cooling, and utilizing warm fluid flowing to the place of cooling to add sensible heat to air after dehumidification and before entrance to the enclosure.

4. Apparatus for conditioning air in an enclosure including a continuous absorption refrigeration system, a duct, means for flowing air through the duct into the enclosure, said refrigeration system including an evaporator positioned in said duct for dehumidifying air flowing therethrough, conduit means for conducting refrigerant fluid and auxiliary fluid to said evaporator for parallel flow in the latter in the presence of each other, and said conduit means being arranged in said duct for reheating dehumidified air before entrance into the enclosure.

5. Apparatus for conditioning air in an enclosure including an absorption refrigeration system containing auxiliary fluid, refrigerant fluid and an absorbent, a duct, means for flowing air through the duct into the enclosure, said refrigeration system including an evaporator positioned in said duct for dehumidifying air flowing

therethrough, and conduit means for separately conducting refrigerant fluid and auxiliary fluid to said evaporator, said conduit means being arranged in said duct for reheating dehumidified air before entrance to the enclosure.

5. Apparatus for conditioning air in an enclosure including a duct, means for flowing air through said duct into the enclosure, an absorp-

tion refrigeration system including an evaporator positioned in said duct for dehumidifying air flowing therethrough, a circuit including said evaporator for circulation of an inert gas, means to conduct refrigerant fluid to said evaporator, and means to reheat the air after dehumidification by heat transfer from gas in said gas circuit.

HUGO M. ULLSTRAND.
